UNITED STATES PATENT OFFICE

2,485,154

ELECTRICAL INDICATOR FOR FREE
PISTON UNITSAndrew Kalitinsky, Eagleville, Conn., assignor to
United Aircraft Corporation, East Hartford,
Conn., a corporation of Delaware

Application January 30, 1945, Serial No. 575,336

10 Claims. (Cl. 230—56)

1

This invention relates to an electrical stroke indicator for free-piston units.

The copending Kalitinsky application, Serial No. 550,883, now Patent No. 2,420,483 dated May 13, 1947, describes a stroke indicator which produces changes in the fluid pressure in a circuit proportional to the changes in the actual end position of the piston stroke. The changes in pressure are used to adjust certain control devices for the unit such as a compression control for the air spring, a fuel timing control, a control for the effective volume of the compressor cylinder or other controls. A feature of this invention is an electrical device by which to indicate changes in the length or position of the piston stroke. Another feature is a stroke indicator for producing changes in an electrical circuit proportional to changes in the actual end position of the piston stroke.

A feature of the invention is a device by which to indicate electrically the actual end position of the piston strokes with respect to the extreme end position of the stroke. Another feature is the continuous electrical indication by changes in an electrical circuit of the changes in the actual end position of the piston strokes, such that these changes may be used in adjusting certain control devices for the unit. A feature of the invention is the electrical control of an actuating device in response to changes in the end position of the piston strokes by which to control a variable operating condition of the unit.

Other objects and advantages will be apparent from the specification and claims, and from the accompanying drawings which illustrate an embodiment of the invention.

Fig. 1 is a sectional view through the unit.

Fig. 2 is a sectional view of the restraining linkage and the master control.

Fig. 3 is a diagram of an electrical circuit including the control.

The unit shown includes an engine cylinder 10 having reciprocating pistons 12 and 14 to which compressor pistons 16 and 18 in cylinders 20 and 22 are integrally connected. Sleeves 24 and 26 are attached to the compressor piston complete the reciprocating piston assemblies. These sleeves in combination with stationary pistons 28 and 30 form air spring cylinders.

The piston assemblies are moved apart by the burning of fuel injected into engine cylinder 10 through one or more nozzles 32. Air compressed in the air spring cylinders on the power stroke returns the piston assemblies. The assemblies are always maintained at equal distances from

the center of the engine cylinder by a linkage which may include racks 34 and 36, Fig. 2, extending from the piston assemblies and meshing with a pinion 38 on a shaft 40.

5 Intake manifold 42 which extends around the compressor and engine cylinders conducts air to intake valves 44 in the heads of the compressor cylinders through which air alternately enters opposite ends of the compressor cylinders. The 10 compressed air leaves the cylinders through discharge valves 46 also at opposite ends of the compressor cylinders and passes into a central scavenge chamber 48 and end chambers 50 and 52. These chambers may be connected by a 15 scavenge manifold, not shown.

Compressed gas from the scavenge chambers enters engine ports 54 and 56 which are uncovered by pistons 12 and 14 at the end of the power stroke, thereby permitting air to be blown 20 through the engine cylinder. Gas in the engine cylinder is discharged through exhaust ports 58 into exhaust manifold 60.

The positions of the pistons at the outer ends of the piston strokes are indicated by a master 25 control 62 actuated by a cam 64 on the shaft 40. Since the pinion 38 on this shaft is oscillated directly from the pistons, movement of cam 64 is proportional to the piston stroke.

The stroke indicator includes a follower 66 30 carrying a roller 68 engaging with cam 64. The follower 66 engages and moves a rod 70 adjacent the outer end of the reciprocation of the follower. The rod 70 has an integral plunger 72 in a chamber 74 in a casing 76. A spring 78 holds the roller 68 against the cam. A spring 80 moves the rod 70 toward the follower, its rate of movement being limited by the plunger which acts as a dashpot and allows the rod to move only a short distance between successive strokes of follower 66. Rod 70 carries an induction coil 82 movable in relation to a fixed coil 84 which may have an open iron core 85 and be shielded by a cover 86.

As shown in Fig. 3 the coil 84 is in series with other coils 88 and 90 in a circuit 92 which includes an oscillator 94 receiving power from supply leads 96. Coil 82 is in series with an oppositely wound coil 98 mounted in fixed relation to coil 88, and coils 82 and 98 are in series with variable resistances 100 and 102 in the same circuit.

50 A lead 106 connects the adjacent ends of the coils 82 and 98 to the adjacent ends of the resistances 100 and 102, thereby forming opposed circuits 108 and 110 one of which includes the coil 82 and resistance 100 and the other of which 55 includes the coil 98 and resistances 102.

Assuming for the moment that the contacts 112 and 114 which engage the resistances 100 and 102 are fixed, and considering instantaneous voltages, a change in the normal position of coil 82 with respect to the surrounding coil 84 will cause an unbalance in circuits 108 and 110, thereby energizing a coil 116, the ends of which are connected to contacts 112 and 114. It will be understood that the circuits 108 and 110 are in balance when the actual end of the stroke of the piston assemblies is normal, and a change in the actual end position of the stroke will unbalance the circuits.

Adjacent to coil 116 is a coil 118 in series in a circuit 120 with the grids 122 and 124 of a vacuum tube 126. A central tap in coil 118 is connected to the cathode 128 of the vacuum tube, and this cathode is also connected to one lead of a coil 130 located in fixed relation to coil 90.

The two plates 131 and 132 of the vacuum tube are connected in series with coils 134 and 136, respectively, and the interconnected ends of these coils are connected to the other lead of coil 130. The coils 134 and 136 are in a position to move a switch bar 138 which controls the direction of rotation of a reversible motor 140 in a circuit 142 which includes contacts 144 and 146 engageable selectively by bar 138.

In operation, when the circuits 108 and 110 are in balance, there is no electrical energy in circuit 120. If the circuits 108 and 110 become unbalanced, by a change in the end position of the piston stroke, coil 116 is energized, thereby inducing a flow of electrical energy in coil 118 to activate the grids 122 and 124. If the electrical impulses in the circuit 120 are in phase with the impulses in the circuit which includes the coil 130, the circuit is completed through grid 122 to coil 134 thereby causing rotation of the motor 140 in one direction. If the impulses in circuit 120 are out of phase with the circuit which includes coil 130, the circuit is completed through grid 124 to coil 136, thereby causing motor 140 to rotate in the opposite direction. The phasing of the impulses in circuit 120 is dependent upon whether the stroke lengthens beyond its normal stroke or shortens to a stroke less than the normal length.

The rotation of the motor 140 is in one direction if the stroke shortens and in the other direction if the stroke lengthens. The rotation of the motor may be used for adjusting the opening of the spill ports by which the effective volume of the compressor may be adjusted, or for adjusting the quantity of fuel, or for adjusting the pressure in the air spring or for such other control as may be desired. To prevent over-control the motor 140 as it rotates also changes the seating of contact 114 on resistance 102, thereby providing a resetting mechanism to stop the motor 140 after a predetermined amount of rotation in either direction.

In order that the control device may be responsive to altitude changes, the contact 112 may be connected to an atmospheric bellows 148 so that the position of the contact 112 is moved in response to changes in atmospheric pressure.

In order to have a direct indication of the position of the end of the piston stroke, an indicator 150 which may be in the form of an A. C. volt meter is connected across coil 82 and may be calibrated to indicate the change in the end position of the stroke, since the change in position will be a function of the change in electrical energy in coil 82.

It is to be understood that the invention is not limited to the specific embodiment herein illustrated and described, but may be used in other ways without departure from its spirit as defined by the following claims.

I claim:

1. In a free-piston unit, a piston assembly, engine and compressor cylinders in which said assembly reciprocates, and means responsive to movement of the piston assembly for indicating electrically the position of the piston assembly in the cylinders, said means including a reversible motor adapted to actuate a control for the unit, an electrical circuit including said motor, a coil movable in response to the piston movement and adapted by its movement to procure changes in the circuit for procuring operation of said motor and means responsive to operation of said motor for procuring changes in the circuit to limit the operation of the motor proportional to the change in the position of the piston assembly.

15 2. In a free-piston unit, a piston assembly, engine and compressor cylinders in which said assembly reciprocates, and means responsive to movement of the piston assembly for indicating electrically the position of the piston stroke of the piston assembly in the cylinders, said means including a reversible motor adapted to operate a control for the unit, an electrical circuit, a coil

20 25 movable in response to the piston movement and adapted by its movement to procure changes in the circuit, means controlled by said circuit for procuring operation of said motor and means responsive to operation of the motor for procuring changes in the circuit to limit the operation of the motor proportional to the change in the position of the piston assembly.

30 35 3. In a free-piston unit, a piston assembly, engine and compressor cylinders in which said assembly reciprocates, said assembly having a variable stroke, and means operative during operation of the unit and responsive to movement of the piston assembly within the cylinders for indicating electrically the end position of the stroke of the piston assembly in the cylinder, said electrical

40 45 means including a fixed coil, a movable coil adjacent to the fixed coil and movable with respect thereto in response to piston movement, said movable coil being connected to and actuated by the piston assembly adjacent to one end of the stroke of the piston assembly, an electrical circuit for supplying energy at a predetermined rate to one of said coils, and electrical indicating means for indicating the change in energy in the other 50 55 of said coils resulting from the relative change in position of the coils when the position of the piston at the ends of successive strokes is changed.

4. In a free-piston unit, a piston assembly, engine and compressor cylinders in which said assembly reciprocates, control means for the unit, and reversible actuating means for said control means, in combination with electrical means responsive to movement of the piston assembly for controlling the direction of movement of said actuating means in response to changes in the end position of the stroke of the piston assembly, said electrical means including a movable coil actuated by and responsive to movement of the piston assembly at one end of the piston stroke, an electrical circuit including said coil and being normally in balance when the end of the piston stroke is at the normal position, and switch means responsive to an unbalance in said circuit for energizing the actuating means.

60 65 70 75 75

5. In a free-piston unit, a piston assembly, engine and compressor cylinders in which said assembly reciprocates, control means for the unit, and an electrical motor adapted to actuate said control means for the unit, in combination with means responsive to changes in the end positions of the strokes of the piston assembly for controlling the motor, said means including a movable coil actuated by and responsive to movement of the piston assembly at one end of the piston stroke, an electrical circuit including said coil and being normally in balance when the end of the piston stroke is at the normal position, and switch means responsive to an unbalance in said circuit for energizing the motor means.

6. In a free-piston unit, a piston assembly, engine and compressor cylinders in which said assembly reciprocates, control means for the unit, and an electrical motor adapted to actuate said control means for the unit, in combination with means responsive to changes in the end positions of the strokes of the piston assembly for controlling the motor, said means including a movable coil actuated by and responsive to movement of the piston assembly at one end of the piston stroke, an electrical circuit including said coil and being normally in balance when the end of the piston stroke is at the normal position, and switch means responsive to an unbalance in said circuit for energizing the motor means, and other means for separately affecting the operation of said motor by changing the normal balance of the circuit.

7. In a free-piston unit, a piston assembly having a variable length stroke, engine and compressor cylinders in which said assembly reciprocates, an air spring acting on said assembly, expansion of gas in the engine cylinder moving the piston assembly in one direction and the air spring moving the assembly in the opposite direction, control means for the unit, and means responsive to movement of the piston assembly for indicating electrically the position of the piston assembly in the cylinder, said means including a reversible motor adapted to actuate the control means for the unit, an electrical circuit, a coil movable in response to the piston movement and adapted by its movement to procure changes in the circuit, and means controlled by the changes in said circuit for procuring operation of said motor.

8. In a free-piston unit, a piston assembly having a variable length stroke, engine and compressor cylinders in which said assembly reciprocates, an air spring acting on said assembly, expansion of gas in the engine cylinder moving the piston assembly in one direction and the air spring moving the assembly in the opposite direction, control means for the unit, and means responsive to movement of the piston assembly for indicating electrically the position of the piston assembly in the cylinders, said means including a reversible motor adapted to actuate the control means for the unit, an electrical circuit, a coil movable in response to the piston movement and adapted by its movement to procure changes in the circuit, a switch controlled by said circuit, and means responsive to changes

in said circuit for moving the switch to control the direction of rotation of the motor.

9. In a free-piston unit, a piston assembly having a variable length stroke, engine and compressor cylinders in which said assembly reciprocates, an air spring acting on said assembly, expansion of gas in the engine cylinder moving the piston assembly in one direction and the air spring moving the assembly in the opposite direction, control means for the unit, and means responsive to movement of the piston assembly for indicating electrically the position of the piston assembly in the cylinders, said means including a reversible motor, adapted to actuate the control means for the unit, an electrical circuit, a coil movable in response to the piston movement at one end of the piston stroke and adapted by its movement to procure changes in the circuit, a switch controlled by said circuit, and means responsive to changes in said circuit for moving the switch to control the direction of rotation of the motor, and other means operating in conjunction with the coil for separately procuring changes in the circuit.
10. In a free-piston unit, a piston assembly having a variable length stroke, engine and compressor cylinders in which said assembly reciprocates, an air spring acting on said assembly, expansion of gas in the engine cylinder moving the piston assembly in one direction and the air spring moving the assembly in the opposite direction, control means for the unit, and means responsive to movement of the piston assembly for indicating electrically the position of the piston assembly in the cylinders, said means including a reversible motor adapted to actuate the control means for the unit, a circuit including a coil movable in response to the piston movement at one end of the piston stroke and adapted by its movement to procure changes in the circuit, and a switch movable in response to changes in the circuit, said switch controlling the direction of rotation of the motor.
